APPARATUS FOR COMBINING SHEETS

Harry A. Rau, Baltimore, Md., assignor to Crown Cork & Seal Company, Inc., Baltimore, Md., a corporation of New York

Application June 26, 1941, Serial No. 399,947

10 Claims. (Cl. 154—36)

The present invention relates to an apparatus for combining or adhesively uniting sheets, such as paper and sheet metal sheets. More particularly, the invention provides a novel combination of instrumentalities for bringing together and adhesively uniting a plurality of sheet metal and paper sheets in an efficient and expeditious manner.

It is an object of the invention to provide an apparatus for feeding from independent stacks, metal and paper sheets and for securing the same together in face to face relation.

A further object of the invention is to provide a machine for adhesively uniting such sheets with their edges in substantially exact registry.

A further object of the invention is to provide improved means for handling independent lines of paper and metal sheets.

A further object is to provide means for bringing together the individual sheets in the two lines in pairs, with their edges registered. Still another object is to handle the registered pairs of sheets, and to maintain the same in registry as they are adhesively united together.

A further object of the invention is to provide novel control means for the lines of paper and metal sheets, to the end that pairs of sheets are always fed to the combining machine.

A further object is to provide positive means for interrupting the feed of sheets in one line, in the event that corresponding sheets in the other line are not present.

A further object of the invention is to provide novel detector means, actuated by the absence of sheets in one line to prevent the delivery of sheets to the other line. To this end, the invention provides novel light sensitive cell means, actuated upon the occurrence of a gap in one of the lines of sheets, to interrupt the delivery of sheets to the other line, thereby to create a corresponding gap in that line so that single sheets are never delivered to the combining machine.

A further object is to provide means for interrupting the delivery of adhesively coated metal sheets to the combining sheet machine, when the delivery of paper sheets to be combined therewith is inadvertently interrupted, thereby preventing the delivery of adhesively coated sheets by themselves to the combining instrumentalities of the machine.

Another object of the invention is to provide novel means for bringing together, in superimposed registered relation, a plurality of metal and paper sheets. To this end, the invention provides a novel combination and arrangement

of conveying means, adapted to deliver lines of metal and paper sheets moving in opposite directions, and to reverse the direction of movement of the line of paper sheets and to superimpose the same, after reversal of their movement, upon the continuously moving metal sheets.

In the accompanying drawings, a preferred embodiment of the invention is shown, but it must be understood that the invention is not limited to the specific details of construction or combination of parts shown therein, as many modifications will occur to one skilled in the art, after considering this disclosure.

In the drawings:

15 Figure 1 is a diagrammatic side elevation of the apparatus of the present invention.

Figure 2 is an enlarged, fragmentary view of a preferred form of reversing roll assembly.

10 Figure 3 is a vertical longitudinal section of the combining machine, proper.

Figure 4 is an enlarged view showing the central section of the machine of Figure 3.

15 Figure 5 is a side elevation of the machine of Figure 3, showing a preferred drive.

Figure 6, 7 and 8 are transverse vertical sections, taken on lines 6—6, 7—7 and 8—8 of Figure 5.

20 Figure 9 is a fragmentary detail view of one of the supporting journals for one of the guide rollers associated with the reversing roll, taken on section 9—9 of Figure 4.

Figure 10 is a fragmentary plan view of a scraper bar assembly for the lower combining roll, said assembly being shown in section in Figure 3.

25 Figure 11 is a sectional detail of one of the supporting journals for the upper infeed roll associated with the combining rolls, and

Figure 12 is a fragmentary side elevation of the drive for said infeed rolls.

30 As shown in Figure 1, the present invention includes a combination of machines, interconnected together for adhesively uniting in face to face relation, a plurality of metal sheets 20 and a plurality of paper sheets 21, the respective sheets being piled in stacks at opposite ends of the apparatus. Although not confined to such use, the invention is of particular utility in uniting lithographed tin-plate sheets and paper liners, employed in the manufacture of

35 receptacle closures of the type shown and described in the patents to Booth, Nos. 1,956,209, 1,956,213, 1,956,215 and 1,956,217. In the manufacture of such closures, tin-plate sheets, 20½ inches in width and 28½ inches in length are

lithographed on their outer surfaces with the individual label for the user of the caps, and paper sheets of the same size are adhesively united to their undersurfaces. For ease of handling, it is usual to coat the non-decorated surfaces of the metal sheets with a layer of adhesive and then to combine therewith, an uncoated sheet of relatively heavy paper. The present invention provides an apparatus for mechanically performing these adhesive coating and sheet combining functions.

Metal sheets 20 are fed from the stack 22 by a mechanical sheet feeder, represented diagrammatically at 24, which may be of the type shown in the patents to Goebel et al. 2,145,764 and 2,184,296. Since the specific details of the sheet feeder are not involved in the invention of this application, they will not be described in detail herein. Reference is made to the aforesaid patents for a complete disclosure of an entirely satisfactory sheet feeder.

The sheet feeder 24 delivers the sheets, one by one, to a conveyor 26 which carries them beneath a detector roller 27 and to a second conveyor 28. The latter, in turn, delivers the sheets to the applicator rolls 29, 30 of a glue-coating machine, which coats the upper, non-decorated surfaces of the sheets with a thin, even coating of adhesive. Since coating machines of suitable type are well-known in the art, the details of construction thereof need not be described herein.

The sheets 20 are delivered from the glue-coating rolls by a conveyor 31 to a plurality of parallel conveyor chains 32, associated with the combining machine proper 35, described in detail below.

The paper sheets 21 in a stack 23 are delivered, one by one, by a sheet feeder 24', which may be similar to the sheet feeder 24, beneath a detector 27', to a conveyor 36, which leads the sheets to the combining machine. As explained in the above identified Goebel et al. patents, the detector 27' is arranged to deflect downwardly any sheets that are fed, inadvertently, by the sheet feeder in pairs or in triplets. In other words, the arrangement is such that only single sheets can be delivered, successively, to the conveyor 36. If two or more sheets stick together and are picked by the suction cups hereinafter referred to, they will be deflected downwardly, by a means described in detail in said patents, to a receiving basket 37. In such case, of course, there will be a gap in the line of paper sheets on the conveyor. As explained in detail hereinafter, means are provided to interrupt the delivery of metal sheets upon the occurrence of a gap in the line of paper sheets.

The paper sheets are delivered successively by the conveyor 36 to a reversing roll assembly 38, where their direction of movement, from right to left in Figure 1, is reversed to a movement from left to right, coinciding with the direction of movement of the metal sheets 20 on the conveyor 32. Pusher means, associated with the conveyor 32, described below, move the superimposed pairs of paper and metal sheets with their rear edges in registry, the paper sheets being spaced above the metal sheet by a supporting platform, described below. The side edges of the sheets are maintained in registry by suitable side guide means. As the pairs of sheets travel, the paper sheets are moved off of the supporting platform and are deposited upon the coated upper surfaces of the metal sheets. They are delivered by the chains 32 in this relation to infeed rollers

39, associated with the pressure applying or combining rolls 40. The latter rolls apply sufficient pressure to the sheets to adhesively unite the paper sheets to the metal sheets and then deliver the combined sheets to a receiving receptacle or jig represented generally at 41, where they are collected in a stack.

It should be noted that the various machines in the combination shown in Figure 1 are interconnected and are driven in predetermined timed relation to each other. Preferably, an electric motor housed in the stand 45 for the glue applicator roll assembly 29, 30, drives a speed reduces 46, having a driving sprocket 47. A chain 48 connects the sprocket 47 to a sprocket on a shaft 50 associated with an angle drive unit 51 having a driving shaft 52 leading therefrom at an angle to the metal sheet feeder 24. Hence, the elements of the metal sheet feeder are actuated in timed relation to the glue applicator rolls and to other instrumentalities, as will be explained.

The shaft 50 of the angle drive assembly carries a pair of additional sprockets, one connected by a chain 53 to a sprocket on shaft 54, about which the conveyor belts 31 are trained. The second sprocket is connected by a chain 55 to a main driving sprocket 56, associated with the combining machine, represented generally at 35. By means shown in Figure 5 and described below, the various parts of the combining machine are driven from the sprocket 56, including a shaft 57 having a sprocket 58 thereon, connected by a chain 59 to a sprocket 60 associated with a second angle drive assembly 61, the latter being connected by a shaft 62 to the paper sheet feeder 24'. Thus, all of the various instrumentalities of the present assembly are driven in unison and at predetermined speed ratios.

The combining machine proper (Figs. 3 and 5) 40 comprises a frame made up of lower horizontal members 65, supported on legs 66, vertical members 67, 68, and upper horizontal members 69. The two rear members 67 are preferably in the form of special castings and carry at their upper 45 ends journals 70 for a transverse shaft 71 having pulleys and sprockets for the conveyor belts 31 and the chains 32. A transverse angle iron 72, secured to the uprights 67, supports longitudinal, inverted T-section members 73, which constitute tracks for the conveyor chains 32. The other vertical end members 68 carry journals 75 for the transverse shaft 57 and, adjacent their upper ends, are connected by transverse frame members 76. Side castings 77 for the combining 55 roll assembly 40 are carried by the horizontal frame members 69, 76 and by the upper ends of the vertical members 68.

Vertically disposed side castings 80 for the various rolls in the combining roll assembly 38 60 are appropriately secured to and are supported by the horizontal frame members 69, vertically disposed supporting posts 81 being disposed therebelow. The castings 80 carry transverse angle bars 82, 83, which, in combination with a similar bar 84 and the transverse bar 72, jointly support the longitudinal T-section members 73. Longitudinally arranged angle bars 85, supported by the transverse bars 82, 84, carry side guide plates 86, adapted to engage the side edges of the sheets 65 as hereinafter explained.

Referring to Figures 3 and 4, the reversing roll assembly supporting castings 80 carry journal brackets 87 for a transverse shaft 88, about which the lower end of the paper sheet infeed conveyor 36 is trained. An infeed roller shaft 89

is journalled in bearings carried in appropriate openings in the castings 80, so that paper sheets delivered by the conveyor 36 ride over the upper surface of the rollers on this shaft. A plurality of guide shoe supporting rods 90, 91 and 92 also have their ends appropriately bolted in apertures in the castings 80, in predetermined spaced relation, each rod having secured thereon a plurality of spaced blocks 83 having guide shoes or plates 84 on their inner surfaces.

Each casting 80 is shaped to provide substantially radially disposed ways 95, 96, 97, carrying journal blocks 88 for guide roll shafts 99, 100, 101, each shaft having secured thereon a plurality of spaced enlargements or rings constituting guide rollers 102, as shown in Figures 7 and 9. The several journal blocks 88 are urged inwardly toward the reversing roll 38' of the assembly 38 by compression springs 103 mounted in caps 104, bolted to the castings 80 and closing the outer ends of the ways 95-97. Hence, the guide rollers 102 are urged into contact with the periphery of the main roll 38'.

The latter roll is secured by heads 105 to a shaft 106, journalled in bearings disposed centrally of the castings 80 and having a sprocket 107 on one of its ends.

The castings 80 also support a transverse bar 110, to the undersurface of which a plurality of forwardly projecting arms 111 are bolted by means of laterally projecting flanges 112. As shown in Figure 7, the bar 110 preferably carries five of these arms.

The castings 80 also carry on their forwardly disposed edge faces journal brackets 113 for an outfeed guide roll shaft 114, the latter having a plurality of rollers 115 secured thereon and disposed substantially in contact with small guide rollers 116, projecting laterally from and carried by the arms 111. A sheet metal platform 117 may be carried by the three middle arms 111 and extended laterally to a line adjacent the outermost T-section track members 73, to assist in supporting the central portions of the paper sheets, or, if desired, the arms 111 alone may serve that purpose.

It will be understood that the paper sheets are delivered by the conveyor 36 to the space below the first series of guide shoes 94, into the bite between the first guide rolls 102 on the shaft 99 and the periphery of the reversing roll 38', which is positively driven, as explained below. The sheets are guided successively between the reversing roll and the guide shoes and guide rolls and are delivered to the upper surface of the arms 111, where they are fed between the positively driven outfeed rollers 115 and the small idler rollers 116 and delivered thereby to the platform 117 or to the forwardly projecting portions of the arms 111.

The metal sheets, simultaneously with the above action, are delivered by the conveyor 31 to the upper surfaces of the chains 32 which are trained for movement below the arms 111 and the platform 117, being supported by the T-section track members 73. The two outermost chains 32 carry a plurality of upwardly projecting pusher-lugs 120, spaced apart on the chains a predetermined distance, somewhat in excess of the longitudinal dimensions of the paper and metal sheets. The pushers engage the rear edges of the metal sheets as they are deposited on the chains and carry them through the machine. Retarding means are provided for the metal sheets, to make sure that their rear edges are firmly engaged by the push-

ers. Preferably, they comprise magnetic blocks 121 (Figs. 3 and 7) carried by brackets 122, secured to the outermost T-section track members 73 and positioned under the path of movement of the metal sheets, in closely spaced relation thereto.

The pusher-lugs 120 project upwardly a short distance above the upper surfaces of the paper sheet supporting arms 111 and platform 117 and engage the rear edges of the paper sheets on the platform. Friction retarding means in the form of a plurality of leaf springs 123 are positioned to engage the upper surfaces of the paper sheets, to make certain that the pusher-lugs engage their rear edges and register them accurately with the metal sheets positioned therebelow. The side edges of the sheets are maintained in registered relation by the side guide plates 86. As the registered sheets are pushed forwardly in unison by the lugs 120, the paper sheets move off of the forward end of the supporting arms or platform and are deposited upon the metal sheets therebelow. In this position, they are fed to the combining roll assembly, now to be described.

The upstanding frame castings 77 for the combining roll assembly are provided with upwardly opening ways 130, in which journal boxes 131 for the shaft 132 of the upper combining roll 133, are mounted. The boxes are adjustably supported from below by bolts 134 threaded into bores in the bottoms of the ways (Fig. 8) to determine the lower limit of movement of the upper roll 133. The shaft 136 of the lower roll 135 is journalled in bearings 137 carried by the frame members 77 below the ways. The rolls are normally set so that the space between their peripheries is slightly less than the combined thicknesses of a metal paper sheet, the coating 35 of adhesive thereon and a paper sheet. Hence, as the sheets pass through, they slightly raise the upper roller 133, against the force of compression springs 138, bearing against the journal boxes 131 and disposed within caps 139 bolted to the frame 40 castings and closing the upper ends of the ways 45 the upper ends of the springs bear against discs 140 carried by adjusting bolts 141 threaded in the caps 139.

As shown in Figure 8, roll shafts 136, 132 carry 50 intermeshing spur gears 142, 143, whereby the rolls are caused to rotate in unison. The gear hubs also carry sprockets 144, 145, adapted to drive the combining roll infeed rolls as herein-after explained. The other end of the roll shaft 55 136 carries a main sprocket 146, adapted to receive rotation from a sprocket chain 147, to drive the combining rolls.

Referring to Figures 3, 6 and 11, between the forward end of the conveyor chains 32 and the 60 combining rolls 133, 135, there is positioned a lower infeed roll 148, fast on a shaft 149 journalled in bearings in the side frame members 77. An upper roller shaft 150 is journalled in vertically slid able blocks 151 guided in ways 152 in 65 the side frame members 77 and supported by yokes 153, straddling the lower roll shaft 149 and carried by the upper ends of vertically reciprocable shafts 154. The shafts 154 are adjustable in length by means of threaded ends 155, 70 156, the latter of which is connected to a member 157 having a cam following roller 158 projecting from its side face and a bifurcated lower end 159, straddling the shaft 57. The shaft 57 carries a pair of cams 160, each having its periphery in engagement with one of the rollers

158, whereby the rods 154 are reciprocated vertically, to raise and lower the bearing blocks 151 for the upper feed roll shaft 150 as the shaft 57 rotates. As shown in Figure 6, the upper shaft 150 carries a plurality of enlargements 161, constituting upper feed rolls, while the lower roll 148 is of uniform diameter from end to end and is preferably rubber-covered.

The feed roll shafts 149, 150 carry sprockets 162, 163 on their ends (Figs. 6 and 12) connected by sprocket chains 164, 165 to the sprockets 144, 145, respectively. Tension rollers 166, 167, carried by bell crank levers 168, 169 and urged toward one another by springs 170, 171, apply suitable tension to the chains and also permit limited vertical movement of the upper sprocket 163 with the upper roll shaft 150.

Referring to Figures 3, 6, 10 and 11, the combining roll assembly frame members 77, adjacent their upper ends, carry a transversely extending rod 175, upon which a scraper blade assembly is mounted. The assembly comprises a transversely extending plate 176 having a plurality of upwardly extending aperture lugs 177 secured thereto and embracing the rod 175, a forwardly projecting scraper blade 178 in contact with the upper roll 133, and a plurality of rearwardly extending, spring arms 179. Tension is applied to the arms 179 by bolts 180 extending therethrough and threaded into blocks 181 carried by a second transverse bar 182.

A somewhat similar scraper blade assembly for the lower roll 135 is provided, reference being had to the same figure. The blade 185 and its backing plate 186 are carried by apertured lugs 187 embracing a transverse bar 188 mounted in the frame members 77. Downwardly projecting arms 189 carried by the blocks 187 have their lower ends positioned adjacent adjusting bolts 190, projecting through a transverse bar 191 and secured in adjusted position by nuts 192, 193. Hence, by adjusting the position of the set screws 190, the arms 189, the blocks 187 and the scraper blade 185 are pivoted about the axis of the rod 187, to apply the desired pressure from the scraper bar 185 to the lower roll 135.

The two scraper blades are provided, in order to maintain the combining rolls in perfectly clean, high polished condition at all times.

As previously pointed out, the sprocket 56 (Figs. 1, 5 and 7) receives rotation from a chain 55, driven by the angle drive assembly 51. The sprocket 56 is fast upon a transverse shaft 195, journaled in bearings carried by the frame castings 80 for the reversing roll assembly. The shaft 195 has a second sprocket 196 thereon, connected to the reversing roll sprocket 107 by a chain 197, whereby rotation is imparted to the latter sprocket. Another sprocket 198 on the opposite end of the shaft 195 is connected by a chain 199 to a sprocket 200, fast on the corresponding end of the outfeed roll shaft 114, whereby the outfeed rollers 115 are rotated. The shaft 195 also carries a spur gear 201, in mesh with a smaller gear 202, carried by a transverse shaft 203 journaled in bearings carried by the horizontal frame members 69. The shaft 203 carries a sprocket 204, connected by a chain 205 (Fig. 5) to a sprocket 206 fast on a counter-shaft 207 which constitutes the main drive for the combining roll assembly, the shaft being journaled in bearings 208, carried by the under surfaces of the main side frame members 69. On one end of the shaft 207, there is a sprocket 209, connected by a chain 210 to the sprocket 146 associated with the

lower combining roll shaft 136. Another sprocket 211 on shaft 207 is connected in driving relation by a chain 212 to a sprocket 213 on the transverse cam shaft 57, to impart rotation thereto and to drive the chain 95 trained about the sprocket 58 on the shaft, which, in turn, drives the angle shaft driving assembly for the paper sheet feeder 24'. A fourth sprocket 214 on the shaft 207 is connected by a chain 215 (Fig. 5) to a sprocket 216 on the shaft 217 for the conveyor chains 32, said shaft being journaled in the side frame castings 77 for the combining roll assembly. As previously explained, the upper combining roll and the infeed rolls 148, 161 on the shaft 150 derive rotation from the lower combining roll 135, by means of the intermeshing gears 162, 143 and the associated sprockets and chains.

When the apparatus is operating normally, paper and metal sheets are delivered by their feeders simultaneously in succession to their respective conveyor lines. It should be noted that the parts are so positioned that there are more paper sheets in the line from the paper stack 21 than there are metal sheets in the metal line from the metal stack 22. Counting the sheet on the top of the paper stack as #1, there are ten successive sheet positions between the stack and the receptacle 41, positioned to receive the combined paper and metal sheets. The second sheet in the paper line is opposite the double sheet detector 27'. The third sheet is opposite an absent sheet detecting station, hereinafter described. The fourth, fifth, sixth and seventh sheets are on the conveyor 36, leading to the reversing roll. The eighth sheet is being reversed or is just being discharged from the reversing roll. The ninth sheet is entering the combining rolls and the tenth sheet is being received by the receiving receptacle 41.

In the metal sheet line, sheets #10, 9 and 8 are combined with or disposed below their corresponding paper sheets, in registered relation. Sheet #7 has just been positioned upon the conveyor 32. Sheet #6, which will correspond to the sheet in the #6 position on the paper sheet conveyor, is emerging from the glue applicator rolls 29, 30. Sheet #5 is on the conveyor 28, while sheet #4 is approaching the double sheet detector device 27. Metal sheet #3, corresponding to the paper sheet at the absent sheet detector station, is on the top of the stack of metal sheets, about to be picked up by the suction cups 225 associated with the metal sheet feeder 24.

Above the narrow belt conveyors 36, at the absent sheet detector station, there are a pair of lights 226, 227, spaced apart a distance greater than the normal spacing between the paper sheets moving along the conveyor, and adapted to project beams of light downwardly between the sheet supporting belts. In the path of the beams of light so projected, there are a pair of light sensitive cell devices 228, 229, connected in series in a circuit 230, including a source of current 231, appropriate relays not shown, and a solenoid 232. These photoelectric cells 228 and 229 act, in a well known manner, as valves and permit the flow of electric current through the circuit 230 only when they are energized by the associated beams of light. Since the cells are in series, current can flow through the circuit only when both cells are energized simultaneously. When the sheets are moving along the conveyor 36 in the normal manner, they pass between the sources of light and the cells and shield the latter when in that position. The cells 228, 229

will be energized alternately, however, by the projection of light downwardly through the spaces between the trailing end of one sheet and the leading end of the next. Because the space between the sheets is less than the longitudinal spacing of the cells, the cells will not be illuminated simultaneously in the normal operation of the apparatus, and the circuit 230 will not be completed through the two cells.

If sheets are projected downwardly, however, by the detector device 21', there will be a gap in the line of paper sheets on the conveyor. Hence, both photoelectric cells 228, 229 will be energized simultaneously and current will flow from the source and, if desired, through appropriate relays, to energize the solenoid 23. The armature of this solenoid is connected by a linkage system, represented diagrammatically at 233, to a valve 234 in the line 235 leading from a suitable source of vacuum, not shown, to the suction cups 225. When the valve 234 is shifted by the energization of the solenoid, communication from the source of vacuum to the suction cups is cut off and the cups are opened to atmosphere through port 236 in the valve 234. Hence, the suction cups 235 associated with the metal sheet feeder 24 will be ineffective to lift a metal sheet from the top of the stack, in the position in the metal sheet line corresponding to the position #3 in the paper sheet line where no paper sheet is present. Therefore, no metal sheet will be delivered to the metal sheet line in position corresponding with this absent sheet in the paper sheet line.

This arrangement is of importance, since otherwise a coated metal sheet would be fed, by itself, to and through the combining rolls, with the result that the layer of adhesive thereon would be transferred to the combining rolls, which, in turn, would apply the adhesive to the surfaces of the succeeding combined sheets and ruin them.

It is thought that the operation of the apparatus of the present invention will be apparent to one skilled in the art from a consideration of the foregoing description. Paper and metal sheets are delivered at the same rate to their respective conveyors 36 and 26, by the sheet feeders 24', 24, respectively. The metal sheets are passed through the glue coating rollers 29, 30, where their upper, non-lithographed surfaces are coated with a continuous, uniform layer of adhesive. They are moved by the conveyor chains 32, beneath the platform 117 and the arms 111, being retarded by the magnetic blocks 121, to cause the pusher lugs 120 carried by the sheets 32 to engage their rear ends.

The paper sheets are delivered by the conveyor 36 to the infeed roll 89 of the reversing roll assembly. The sheets are held in firm contact with the periphery of the reversing roll 38' by the guide rollers 102 and the guide plates or shoes 94. Therefore, they move around upon the periphery of the roll and are delivered to the upper surfaces of the sheet supporting arms 111 and are fed outwardly upon the platform 117 by the outfeed rollers 115, cooperating with the small rollers 116. Movement of the paper sheets along the platform is retarded by the leaf spring members 123, so that the pushers engage their rear ends and register the paper sheets with the metal sheets. As the paper sheets are moved off of the front end of the platform, they are deposited upon the upper, adhesively coated surfaces of the metal sheets. As the lightly com-

bined sheets approach the infeed rollers 148, 161, the upper roll shaft 150 is in raised position as a result of the action of the cam 160 which supports cam follower 158. Thus, the sheets meet 5 no resistance as they enter the bite between these feed rollers. The cam 160 is so timed with respect to the pusher lugs on the chains 32 that, as soon as the combined sheets have been inserted between the separated feed rollers, the upper roll 10 drops and frictionally engages the combined sheets and positively forces the same forwardly until the leading edges of the sheets have been positively entered into the bite between the positively driven combining rolls. Thereupon, the 15 feed rollers separate and the sheets are drawn through the combining rolls by the rotation thereof. The infeed rolls remain in separated position until the next pair of sheets have been inserted therebetween, whereupon the cycle is repeated.

The combined sheets, adhesively united together by rolling contact with the combining rolls, may be deposited automatically in an appropriate receptacle, as shown diagrammatically at 41, or 20 they may be manually stacked by an operator.

It must be understood that the invention is not limited to the specific details of construction described above and shown in the accompanying drawings, or to the particular sequence of method 30 steps, since many modifications will readily occur to one skilled in the art, from a consideration of this disclosure. The invention includes all modifications coming within the scope of the appended claims and their equivalents.

35 I claim:

1. In combination, a machine for adhesively uniting paper and metal sheets, a paper sheet feeder spaced therefrom, a metal sheet feeder spaced therefrom, a conveyor between each sheet 40 feeder and said machine, means for projecting a beam of light across one of said conveyors, light sensitive cell means positioned to be energized by the absence of a sheet in normal position on the last-mentioned conveyor, and means controlled by said cell means for rendering inoperative the sheet feeder associated with the other conveyor, whereby no sheet will be delivered by the latter feeder to the associated conveyor in the position corresponding to the position on the other conveyor of the absent sheet thereon.

50 2. In combination, a machine for adhesively uniting paper and metal sheets, separate conveyors leading to said machine adapted to deliver independent lines of individual paper and metal sheets in predetermined spaced relation for union 55 in said machine, a metal sheet feeder adapted to deliver the individual metal sheets to one conveyor, a paper sheet feeder adapted to deliver the paper sheets to the other conveyor, but spaced a greater distance from the said machine than the first feeder, means associated with the paper sheet conveyor adjacent the paper sheet feeder for detecting the absence of a sheet in the line thereon in the position normally to be combined with the metal sheet then in position to be fed to the first-mentioned conveyor by the metal sheet feeder, and means controlled by the detecting means for rendering the metal sheet feeder inoperative to deliver that metal sheet to its conveyor in said position to be combined with the absent paper sheet.

60 3. In combination, a machine for combining paper and metal sheets, a pair of independent conveyors leading to said machine, means for delivering 65 a line of metal sheets in predetermined spaced 70 75

relation to one conveyor, means for delivering a line of paper sheets in similarly spaced relation to the other conveyor, whereby the sheets are normally delivered to the machine in pairs of corresponding paper and metal sheets, detector means disposed in operative relation to one conveyor and arranged to be actuated by the inadvertent absence of a sheet moving in the line on that conveyor, and means controlled by the actuation of said detector means to render inoperative the means for delivering a sheet to the other conveyor, thereby preventing the delivery of only a single sheet to the sheet combining machine.

4. In combination, a machine for combining paper and metal sheets, a pair of independent conveyors leading to said machine, means for delivering a line of metal sheets in predetermined spaced relation to one conveyor, means for delivering a line of paper sheets in similarly spaced relation to the other conveyor, whereby the sheets are normally delivered to the machine in pairs of corresponding paper and metal sheets, means for projecting a beam of light across the paper sheet conveyor, light sensitive cell means positioned to be energized by said beam of light in the absence of a sheet in the line on that conveyor, and means controlled by said cell means for rendering inoperative the means for delivering a metal sheet to the other conveyor, thereby preventing the delivery of metal sheets by themselves to the combining machine.

5. In combination, a machine for combining paper and metal sheets, a pair of independent conveyors leading to said machine, means for delivering a line of metal sheets in predetermined spaced relation to one conveyor, means for delivering a line of paper sheets in similarly spaced relation to the other conveyor, whereby the sheets are normally delivered to the machine in pairs of corresponding paper and metal sheets, means for projecting across the paper sheet conveyor, two beams of light spaced apart a distance greater than the normal space between the sheets on the conveyor, a pair of correspondingly spaced light sensitive cells in the path of said beams, whereby the cells are normally alternately shaded by the paper sheets on the conveyor, an electric circuit connecting the cells in series, and means controlled by said circuit for rendering inoperative the means for delivering a metal sheet to the other conveyor, when both of said cells are energized simultaneously by the absence of a sheet in normal position on the first conveyor.

6. In an apparatus of the class described, a conveyor adapted to move a line of paper sheets in one direction, and a reversing roll assembly for receiving said sheets and delivering the same for movement in substantially the opposite direction, said assembly comprising a horizontally mounted,

positively driven, relatively large roll, guide means for delivering the sheets from the conveyor to the upper periphery of the roll, a plurality of spaced guide rollers in contact with the periphery of the roll, and a plurality of stationary guide means spaced from the periphery of the roll and positioned between the guide rollers.

7. In an apparatus of the class described, a conveyor adapted to move a line of paper sheets in one direction, a reversing roll assembly for receiving said sheets and delivering the same for movement in substantially the opposite direction, said assembly comprising a relatively large, positively driven roll, a smaller, positively driven infeed roll adapted to deliver the sheets to the periphery of the first-mentioned roll, and a plurality of guide plates and guide rollers alternately spaced around a portion of the periphery of the first roll, to guide the sheets for movement therewith.

8. In an apparatus of the class described, a conveyor adapted to move a line of paper sheets in one direction, a reversing roll assembly for receiving said sheets and delivering the same for movement in substantially the opposite direction, said assembly comprising a relatively large, positively driven roll, a smaller, positively driven infeed roll adapted to deliver the sheets to the periphery of the first-mentioned roll, a plurality of guide plates and guide rollers alternately spaced around a portion of the periphery of the first roll to guide the sheets for movement therewith, means for receiving the sheets after such movement, and outfeed roll means for advancing the sheets relative to the receiving means.

9. In an apparatus of the class described, a paper sheet reversing roll assembly, means for delivering paper sheets moving in one direction thereto, a platform for receiving the sheets from the roll, and means for moving the sheets along said platform in a direction opposite to the first direction, said reversing roll assembly comprising a positively driven, relatively large roll, and means for guiding the sheets for movement with said roll around the periphery thereof.

10. In combination, means for continuously conveying a plurality of pairs of superimposed, registered metal and paper sheets with a layer of adhesive interposed therebetween, a feed roll assembly, and a pair of pressure applying combining rolls, said feed roll assembly comprising a pair of rolls, means for separating the rolls in timed relation to the movements of the sheets on the conveying means, whereby the sheets enter the rolls when separated, and means for converging the rolls to apply positive feed pressure to the sheets, to deliver them to the combining rolls.
